UNITED STATES PATENT OFFICE.

SEBASTIAN PERRONE, OF NEW YORK, N. Y.; LOUISA PERRONE, OF NEW YORK, N. Y.,
ADMINISTRATRIX OF SAID SEBASTIAN PERRONE, DECEASED.

HAIR-CUTTER.

1,023,786.

Specification of Letters Patent.

Patented Apr. 16, 1912.

Application filed June 15, 1911. Serial No. 633,280.

To all whom it may concern:

Be it known that I, SEBASTIAN PERRONE, a citizen of the United States, and a resident of the city of New York, borough of 5 Manhattan, in the county and State of New York, have invented a new and Improved Hair-Cutter, of which the following is a full, clear, and exact description.

This invention relates to hair cutters, for 10 use by barbers and others in trimming the hair, and has reference more particularly to a device of this class which comprises a holder having a blade socket, a blade arranged in the socket and having the edge 15 projecting beyond the same, and a member separably associated with the holder and extending over the socket and the blade, and beyond the latter, and provided with comb teeth.

20 The object of the invention is to provide a simple and efficient hair cutter by means of which each individual can cut his own hair quickly and easily, without the assistance of a barber or any other person, which 25 permits the hair to be cut uniformly and as short as desired, which requires no special skill on the part of the user, and which can be inexpensively manufactured.

The invention consists in the construction 30 and combination of parts to be more fully described hereinafter and particularly set forth in the claims.

Reference is to be had to the accompanying drawings forming a part of this specification, in which similar characters of reference indicate corresponding parts in all the views, and in which—

Figure 1 is a plan view of an embodiment 40 of my invention; Fig. 2 is an edge view of the device showing a part in cross section; and Fig. 3 is a transverse section on the line 3—3 of Fig. 1.

Before proceeding to a more detailed explanation of my invention it should be 45 clearly understood that while the hair cutter is of assistance to barbers in the practice of their profession, it is intended particularly for use by individuals to enable them to cut their own hair, and thus to obviate the necessity of the services of a barber or other skilled hair cutter. As will be 50 readily understood, when the hair is cut by means of a scissors and comb in the usual manner it is very difficult to prevent 55 the formation of ridges or inequalities, and

complete uniformity of the surface is acquired with difficulty. With my invention however, the hair is shaved or planed so that the ends of the hair are trimmed evenly and all unsightly irregularities are thus 60 avoided. The device consists of but three parts, can be readily assembled and taken apart, and can therefore be kept in a clean and sanitary condition with the greatest of 65 ease.

Certain of the details of construction shown for example herewith, form no part of the invention, and can be varied in accordance with individual preference and special conditions, without deviating from 70 the essence of the invention as defined in the appended claims.

Referring more particularly to the drawings, I have shown for example, an embodiment of my hair cutter which has a holder 75 10 fashioned from sheet metal or any other suitable material, and provided near its lower edge with an inclined, offset 11 formed by stamping in a die or any other convenient manner. The offset constitutes a socket 80 for the cutting blade 12. This may approximate the ordinary safety razor blade, or may have any other preferred or common form. The socket has sides 13 which prevent the lateral displacement of the 85 blade, which normally lies in a plane substantially that of the body of the holder 10.

At the lateral edges, the holder has in-turned, offset flanges 14 under which is slidably received a plate 15 which extends 90 over the socket and the blade, and serves to hold the latter in position. At the lower edge, the plate projects beyond the blade 95 and is provided with a plurality of teeth 16 so that it constitutes a comb. The end 18 teeth 17 of the comb have projections 18 constituting stops to engage at the ends of the blade, and serving to hold the same in position when the parts are assembled.

To separate the parts it is merely necessary to slide the member 15 from engagement with the holder. The blade can thus be readily lifted from the socket; the three parts constituting the socket can thus easily be cleansed and kept in a sanitary condition. 100 When the hair cutter is in use it is held in one hand or the other and the comb teeth are passed through the hair as if it were being combed. The ends of the hair which 105 come in contact with the cutting edge of the 110

blade are thus severed, and the hair can be cut as short as desired by suitably repeating the operation.

Having thus described my invention, I claim as new, and desire to secure by Letters Patent:

1. A hair cutter consisting of three parts only, one of said parts being the holder and comprising a thin, flat plate having a flat, 10 angularly disposed offset constituting a blade socket and having the edge lying substantially in the plane of the plate, said plate being forwardly bent at the lateral margin, to form in-turned flanges, the second of said parts being a blade removably located in said socket and extending over the edge thereof, and the third of said parts being a thin, flat plate slidably and removably held under said flanges, against said 20 holder and over said socket, said last-mentioned plate having a plurality of comb teeth, the end ones of said teeth being provided with projections adapted to engage at the ends of said blade and constituting stops 25 therefor.
2. A hair cutter substantially as described,

comprising a body portion consisting of a main plate whose lateral edges are returned to form keeper flanges, and having an offset constituting a blade socket, said flanges terminating at said socket, said plate having at the lateral edges of said socket upturned portions, said socket with its upturned ends serving to give rigidity to such portions of the body, and the lateral flanges of said 35 body aiding in giving rigidity to such part of the body, a blade adapted to fit in said socket with its outer side or face substantially in a plane with that of the main plate, and a retaining plate removably held by 40 said keeper flanges of said main plate and overlying the blade and having at its forward edge teeth projecting beyond the cutting edge of said blade.

In testimony whereof I have signed my 45 name to this specification in the presence of two subscribing witnesses.

SEBASTIAN PERRONE.
